[57] CLAIM

The ornamental design for a monitor mount, as shown and described.

DESCRIPTION

FIG. 1 is an isometric view of a monitor mount constructed in accordance with a preferred embodiment of the invention, the monitor mount being shown in a retracted orientation with a monitor in dashed lines for illustrative purposes only and forming no part of the claimed design;

FIG. 2 is an isometric view thereof, with the monitor mount in an extended position;

FIG. 3 is a left-side view of the monitor mount;

FIG. 4 is a right-side view thereof;

FIG. 5 is a top view of the monitor mount while in the retracted orientation;

FIG. 6 is a front elevational view of the monitor mount while in the retracted orientation;

FIG. 7 is a bottom view of the monitor mount while in the retracted orientation; and,

FIG. 8 is a rear view of the monitor mount while in the retracted orientation.
